DESIGN FOR A PERMANENT WAVING
MACHINE

Otto Seiter, Wallingford, Conn., assignor to The
Nestle-Le Mur Company, Meriden, Conn., a cor-
poration of Ohio

Application January 18, 1949, Serial No. 285

Term of patent 3½ years

(CL. D86—10)

To all whom it may concern:

Be it known that I, Otto Seiter, a citizen of the United States, residing at Wallingford, in the county of New Haven and State of Connecticut, have invented a new, original, and ornamental Design for a Permanent Waving Machine, of which the following is a specification, reference being had to the accompanying drawing, forming part thereof.

In the drawing:

Fig. 1 is a three-quartered front perspective view of a permanent waving machine, showing my new design;

Fig. 2 is a top view thereof; and

Fig. 3 is a side view.

I claim:

The ornamental design for a permanent waving machine, substantially as shown.

OTTO SEITER.
